GRINDING MACHINE FOR RAILWAY TRACKS

Henry H. Talboys, Milwaukee, Wis., assignor to
Nordberg Manufacturing Co., Milwaukee, Wis.,
a corporation of Wisconsin

Application August 19, 1931, Serial No. 557,969

6 Claims. (Cl. 51—178)

My invention relates to an improvement in grinding machines for railroad tracks and has for one purpose the provision of a simple, light and efficient grinder which may be mounted upon or moved along a railway track and which may be readily removed from the track. Another object is the provision of an improved control means or clutch adaptable for use with the grinder or with other power driven mechanisms. Other objects will arise from time to time in the course of the specification and claims.

I illustrate my invention more or less diagrammatically in the accompanying drawings wherein

Figure 1 is a side elevation;

Figure 2 is an end elevation;

Figure 3 is a section on a line 3—3 of Figure 1;

Figure 4 is a similar section with parts in a different position;

Figure 5 is a section on the line 5—5 of Figure 3 with parts omitted;

Figure 6 is a section on the line 6—6 of Figure 1;

Figure 7 is a section on a line 7—7 of Figure 6;

Figure 8 is a view similar to Figure 3 of a variant form;

Figure 9 is a section on the line 9—9 of Figure 8;

Figure 10 is a view similar to Figures 3 and 8 of a further variant form; and

Figure 11 is a section on the line 11—11 of Figure 10.

Like parts are indicated by like symbols throughout the specification and drawings.

Referring to the drawings, AA indicate the rails of a track. Spanning these rails is the transverse shaft A¹ which is provided at one end with any suitable roller A² of insulating material. Rubber is a practical material for this purpose.

The shaft A¹ is secured at its opposite end to a base frame generally indicated as B. The frame may include the yoke shaped or longitudinally extending angles B¹ which are connected as by the horizontal channels B². The ends of the channels B² may be connected by the arcuate channel portions B³. Downwardly depending from the angles B¹ are the flanges B⁴ to which the shaft A¹ is actually secured. Other depending flanges are members B⁵ which receive the transversely extending axles B⁶ of the flanged rollers B⁷, which rollers are provided at each end with flanges B⁸ conforming generally to the form and width of the tread portions of the rails A.

C generally indicates any suitable motor structure mounted on the above frame work. It in-

cludes a shaft C¹ carrying a fly-wheel C² which also serves as drive-wheel. The fly-wheel C² may be channeled as at C³ to receive the V-shaped belting generally indicated as C⁴. The belt or belts employed pass also about a driven pulley C⁵.

The pulley C⁵ is provided with a shaft or axle D which rotates in the bearings D¹ at opposite ends of a cylindrical sleeve D², which sleeve is mounted on the bracket members D³, which in turn are rotatably mounted as at D⁴ upon the angle members D⁵ associated with the frame B. The brackets D³ include split portions D⁶ bolted together about the cylinder D² as by the bolts D⁷. The arc of rotation of the brackets D³ may be limited, as by the stop D⁸. Associated with the brackets D³, for example, being welded thereto, is the lever structure D⁹ with the lever extension proper D¹⁰ which is provided with a spring D¹¹, which may be secured to any suitable securing means, for example a link of the chain D¹², one link of which may be secured or welded to an arcuate member B³. When the parts are in the position as seen in Figures 2 and 3, the pulley C⁵ is rotated about the center D⁴ in a counter clockwise direction, and this holds the belting C⁴ tightly about the drive-wheel C², in driving relationship therewith.

It will be observed, as in Figure 3, that the spring D¹¹ normally urges one pulley away from the other into a driving relationship. It will be understood, however, that in case the device is subjected to a predetermined overload sufficient to overcome the strength of the spring D¹¹, the spring will give and permit a shortening of the distance between the pulleys, whereby the upper side of the belt will become so loose as to permit slippage to occur. The arrow indicates the direction of rotation, the lower belt being the tight side of the belt.

E indicates a guide for the lower turn of the belt C⁴. It is shown as straight, except for the ends which are downwardly turned or curved as at E¹. It may be mounted as on the bracket member E². It conforms generally to the location of the lower reach of the belt C⁴ when it is in driving relationship, but is spaced slightly downwardly therefrom to prevent frictional contact when driving. E³ indicates an upper belt guide which is provided with an arcuate portion E⁴ conforming generally to the arc of the pulley C⁵, said guides being secured by bracket members E⁵ to the hinged brackets D³. The rectilinear guide E³ is spaced away from the upper reach of the belt C⁴ when the parts are in driving relationship, as shown in Figure 3. When the operator re-

leases the spring D¹¹ from the chain D¹² the pulley C⁵ may swing by its own weight into the position in which it is shown in Figure 4. The guide portions E³ and E⁴ may engage the belt and cause it to bulge out and take the position in which it is shown in Figure 4. Preferably the belting C⁴ is molded to form a circle and tends to expand, when released, into full circular form. However, it is confined between the guides E, E³ and E⁴, and is therefore, constrained to bulge out as shown in Figure 4. This bulging removes it from driven contact with the fly-wheel or drive-wheel C² of the motor. The motor may be constantly driven, and the mounting of the pulley C⁵, in cooperation with the guides E, E³, and E⁴, acts as a very simple form of clutch. A main purpose for permitting release of the belt C⁴ from driven connection with the drive-wheel C² is to permit the engine to be started. In order to shield the pulleys and belt and for safety means I may provide a guard plate E⁶, which may be welded to the guide E.

In order to permit the ready manual movement of the grinding device as a whole I may employ the longitudinally extending carrying bars G¹ which may be welded or otherwise secured to the arcuate members B³ and which extend a sufficient distance to permit a pair of operators to lift the entire device and carry it like a sedan chair.

I do not wish to be limited to any specific detail of grinding member but I illustrate the following as a practical exemplification of my invention. H indicates a grinding disc of abrasive material. It may be confined between the two clamping members H¹, H² and the clamp nut H³ which is in screw threaded relationship with the outer end H⁴ of the shaft H⁵ which rotates within bearings H⁶ within a handle cylinder H⁷. H⁸ is any suitable support for an arcuate guard H⁹ which carries a handle H¹⁰. H¹¹ is any suitable U-shaped member which may carry an additional handle H¹². The shaft H⁵ is connected, as by a flexible shaft H¹³ with the shaft D as shown in Figure 5. H¹⁴ is any suitable surrounding flexible cover.

Referring to the form of Figures 8 and 9 I illustrate a device in which different means are employed for moving the belt or belts C⁴ into and out of driving relationship with the pulley C². The pulley C⁵ is in this case mounted upon fixed brackets or supports I, which may correspond with the members D³ except in that they are held against rotation. Therefore, the axes of rotation of the pulleys C² and C⁵ are relatively fixed. The belt C⁴ is confined by upper and lower generally rectilinear guide members I¹ and I² which are joined by the arcuate guide portion I³. The belt C⁴ being molded to a complete circle, it tends to take the dotted line position of Figure 8, if released. In such position it is held by the guides in such fashion as to cause it to bulge out into the inoperative position illustrated in dotted line, out of contact with the pulley C². In order to effect a driving connection between the pulleys C² and C⁵ I provide belt tightening means which may include, for example, the idler I⁴ mounted at the end of the links I⁵, which are pivoted as at I⁶ to the upstanding fixed support I⁷. On this support is a bracket or abutment I⁸ which is adapted to receive the lower end of the locking member or dog I⁹, which is pivoted to one of the links I⁵. I¹⁰ is a coil spring which may be secured to the frame as at I¹¹ and to the link I⁹ as at I¹². The spring normally draws the parts into the full line

position of Figure 8. The member I⁹ may be employed to hold the parts in the dotted line position, either against the spring I¹⁰, or in the event that the spring I¹⁰ is detached from the frame against the weight of the idler I⁴ and the links I⁵. I¹³ indicates a handle associated with the links I⁵. I¹⁴ indicates a short guide positioned beyond the idler I⁴ and in line with the guide I².

Figures 10 and 11 illustrate a further variation in which the idler L is employed to draw outwardly upon the belt C⁴ in order to tighten it. The idler is shown as mounted upon the extremities of the links L¹, which are pivoted to the frame as at L². Pivoted concentrically with the idler L are the links or arms L³, L⁴ which are themselves pivoted respectively to pivoted guides L⁵, L⁶. A spring L⁷ is employed, for example, in connection with the chain L⁸ for holding the parts in the full line on operative position of Figure 10. L⁹ indicates a locking member pivoted on the links L¹, which may be moved into the dotted or locking position in opposition to the locking abutment L¹⁰. It is to be understood in this form, as in the others, the belt is constrained by the guides to inoperative position. The circularly formed belt positively thrusts itself into inoperative position when it is released within the space defined by the guides.

It will be realized that whereas I have shown a practical and operative device, nevertheless many changes may be made in size, shape, number and disposition of parts without departing from the spirit of my invention. I, therefore, wish my drawings to be taken as in a broad sense illustrative and diagrammatic, rather than as limiting me to the details of the device as herein described and shown.

The use and operation of my invention are as follows:

A typical embodiment of my invention is a grinding and cutting machine which is particularly applicable for use on the rails of a railway track. It may for example include a framework, as shown in Figure 2, balanced above one rail, but supported as by the transversely extending supporting member A¹. Since the center of weight of the motor is between the two rails, the weight of the motor and the platform upon which it is mounted holds the member A¹ with its insulating contact A² in the position in which the parts are shown in Figure 2. An advantage in spotting the engine, for example a gasoline engine, over one rail, causes the rail to take the vibration of the engine. The drive wheel C² of the engine drives the pulley D⁷, which pulley is in direct driving connection with the flexible power transmission H¹³ which extends to any suitable track working member. I might employ a wide variety of such members but I have shown only the grinding disc H. The member H is preferably housed by the guard H⁹, which has the two handles H¹⁰ and H¹².

An important feature of my device is the clutch connection between the drive member C² and the driven member C⁵. Preferably I employ a molded belt C⁴, or a plurality of such belts. Such belts may be so formed as to tend to take a circular shape, or a shape conforming more closely to a circle than the space defined by the opposed guards E, E³. In the form shown in Figures 3 and 4 I associate the guard E³ with the links D³ in such fashion that when the pulley C⁵ is moved toward the drive wheel C² the guard E³ takes the position shown in Figure 4. The tendency of the belt C⁴ to conform to a circle is resisted by the

confining effect of the opposed guides E and E³. As the pulley C⁵ has approached the drive wheel C², the slack of the belt so provided bulges out as shown at the right of Figure 4, out of frictional contact with the constantly rotating drive member C².

The form of Figures 8 and 9 varies, in that the pulley C⁵ rotates about a fixed axis. The slack is normally taken up by the idler I⁴. When the 10 idler I⁴ is moved, against the spring I¹⁰, then the bulging action characteristic of the above described form takes place.

In the form of Figures 10 and 11 the idler L is positioned within instead of without the belt 15 C⁴, and the guide members L⁵ L⁶ move with it. The bulging action, however, is substantially the same.

I claim:

1. In a track working machine, a base frame, 20 means for positioning said frame on a rail of said track, a motor mounted on said frame, the axis of rotation of said motor being parallel with said rail, a balancing connection extending from said frame to the other rail of the track, the frame 25 and the parts thereon being in substantial balance upon the single rail over which they are positioned but overbalanced slightly toward the adjacent rail, a track working driving shaft mounted for rotation about an axis substantially 30 parallel to the axis of the motor and positioned laterally thereof between the rails, and a carrying frame including transversely positioned up-standing yoke members straddling the motor and tool driving shafts, and a plurality of longitudinally 35 extending carrying bars secured to said yoke members on opposite sides of the motor axis.

2. In a track working machine, a base, a plurality of track engaging rollers rotatably mounted 40 on said base, said rollers being provided with axially spaced flanges and being adapted for alignment upon a single rail of a track, a tubular member extending laterally from said base, and extending toward the opposite rail of the track, an insulating contact member upon said tubular 45 member, adapted to contact with said opposite rail, a motor mounted upon said base, the axis of rotation of said motor being parallel with the rail, said motor and base being in substantial 50 balance upon the single rail over which they are positioned, but overbalanced slightly toward the adjacent rail, and a carrying frame secured to said base, said frame including generally arcuate members lying in planes at right angles to said rail and connected at their lower ends to said 55 base, said arcuate members being connected by longitudinal elements extending substantially beyond said arcuate members in each direction, said extending portions being adapted to serve as carrying handles for the track working machine.

3. In a track working machine, a base, a plurality of track engaging rollers rotatably mounted 60 on said base, said rollers being provided with axially spaced flanges and being adapted for alignment upon a single rail of a track, a tubular member extending laterally from said base, and adapted for engagement with the opposite rail of the track, a motor mounted upon said base, the axis of rotation of said motor being parallel with the rail, said motor and base being in substantial 65 balance upon the single rail over which they are positioned, but overbalanced slightly toward the adjacent rail, and a carrying frame secured to said base, said frame including generally arcuate members lying in planes at right angles to

said rail and connected at their lower ends to said base, said arcuate members being connected by longitudinal elements extending substantially beyond said arcuate members in each direction, said extending portions being adapted to serve as carrying handles for the track working machine.

4. In a track working machine, a base, a plurality of track engaging double flanged rollers rotatably mounted on said base and aligned upon a single rail of a track, a transverse member 10 extending laterally from said base toward the adjacent rail of the track, a motor mounted upon said base, motor and base being in substantial balance upon the single rail over which they are positioned, but overbalanced slightly toward the 15 adjacent rail, and a carrying frame secured to said base, said frame including generally arcuate members lying in planes at right angles to said rail and secured at their lower ends to the base, said arcuate members being connected by 20 longitudinal elements, said longitudinal elements having handle extensions substantially beyond the arcuate members.

5. In a track working machine, a base, a plurality of track engaging double flanged rollers 25 rotatably mounted on said base and aligned upon a single rail of a track, a transverse member extending laterally from said base toward the adjacent rail of the track, a motor mounted upon said base, motor and base being in substantial 30 balance upon the single rail over which they are positioned, but overbalanced slightly toward the adjacent rail, and a carrying frame secured to said base, said frame including generally arcuate members lying in planes at right angles to 35 said rail and secured at their lower ends to the base, said arcuate members being connected by longitudinal elements, said longitudinal elements having handle extensions substantially beyond the arcuate members, a drive pulley associated 40 with said motor, a driven pulley, laterally spaced from said drive pulley, supported on said base, a driving belt surrounding said pulleys the axes of driving and driven pulleys being parallel and a flexible shaft driven by said driven pulley and 45 a grinding tool at the extremity of said flexible shaft.

6. In a track working machine, a base, a plurality of track engaging double flanged rollers rotatably mounted on said base and aligned upon 50 a single rail of a track, a transverse member extending laterally from said base toward the adjacent rail of the track, a motor mounted upon said base, motor and base being in substantial balance upon the single rail over which they 55 are positioned, but overbalanced slightly toward the adjacent rail, and a carrying frame secured to said base, said frame including generally arcuate members lying in planes at right angles to said rail and secured at their lower ends to the base, said arcuate members being connected by longitudinal elements, said longitudinal elements having handle extensions substantially beyond 60 the arcuate members, a drive pulley associated with said motor, a driven pulley, laterally spaced from said drive pulley, supported on said base, a driving belt surrounding said pulleys the axes of driving and driven pulleys being parallel and a flexible shaft driven by said driven pulley and 65 a grinding tool at the extremity of said flexible shaft, and a link upon which said driven pulley is mounted, said link being pivotally supported in relation to said base.

HENRY H. TALBOYS.
